CLAIM

The ornamental design for a target holder, as shown and described.

DESCRIPTION

FIG. 1 is another perspective view of the target holder showing another alternate configuration;

FIG. 2 is a top plane view thereof;

FIG. 3 is bottom plane view thereof;

FIG. 4 is a left side elevation view thereof, the right side being a mirror image;

FIG. 5 is a front elevation view thereof;

FIG. 6 is a rear elevation view thereof; and,

FIG. 7 is another perspective view of the target holder of FIG. 1 shown with example targets installed thereon for environmental purposes.

In the Figures the dash-dash broken lines are for the purpose of illustrating environment and form no part of the claimed design.
